UNITED STATES PATENT OFFICE

JAMES B. BAKER, OF SCENERY HILL, PENNSYLVANIA

MILK BOTTLE STERILIZER

Application filed August 12, 1930. Serial No. 474,855.

My invention consists of an improvement in means for sterilizing bottles or the like, by passage therethrough of a continuous curved column or series of the bottles, for the purpose of cleansing and sterilizing, and delivering the bottles one by one continuously at the delivery end of the apparatus.

The device consists of a main enclosing tank, adapted to contain a body of water or other sterilizing fluid, capable of being set upon a stove or over a burner, for heating, and provided with a removable top, and one or more downwardly curved perforated conductor pipes or tubes for movement of the bottles therethrough, as will be more fully hereinafter described.

Referring to the drawings, showing one preferred embodiment of the invention:

Fig. 1 is a plan view of the device;

Fig. 2 is a longitudinal sectional view on the line II—II of Fig. 1 with the tank;

Fig. 3 is a side view in elevation, partly broken away;

Fig. 4 is a vertical section on the line IV—IV of Fig. 3;

Fig. 5 is an enlarged cross section of the bottle conducting tube.

Referring to the drawings, 2 is the main enclosing tank or vessel, of any desired design, made of sheet metal or other suitable material, and properly shaped for economy of space to admit of the insertion therein of the article circulation tube or tubes.

For such purpose the base or bottom 3 of tank 2 is somewhat shorter than its top, the end walls 4 sloping upwardly and outwardly, providing the elongated upper portion, upon which is placed the removable cover 5.

Such cover may be provided with suitable handles 6 and may be laid upon the top edges, or provided with inner or outer flanges for tight connection therewith, in the manner customary in making covers or tops for boilers, pots, and the like.

Fixedly connected with the top 5 is the bottle conducting tube or conduit 7, preferably circular in cross section and of a size to freely admit for passage therethrough a continuous series of bottles or other open-

ended containers 8, as clearly indicated in Fig. 2.

Tube 7 is connected at opposite ends of the cover 5 in any suitable manner so as to make it a fixture therewith, and depends inwardly at an angle at each end and rounded downwardly in the form of an arc, as shown.

The receiving end of tube 7 preferably terminates flush with the top 5 while the delivery end 9 preferably extends slightly above the top as shown, for suitable reception and delivery of the articles to be cleansed.

By extending the delivery end of the tube somewhat above the top of the tank, the bottles may be easily discharged upon a conveyor of suitable kind.

Tube 7 is submerged, as to its middle portion, below the water line *a*, a gauge 10 being preferably utilized to indicate the temperature of the water.

Tube 7 is provided throughout the lower middle portion of its length with a series of perforations or openings 11, more or less closely adjacent, perforating the tube at intervals through its sides and bottom as may be desired, so as to provide for free circulation of water.

The water being sufficiently heated to the desired temperature, the bottles are inserted with the closed end down into the tube 7 at its receiving end, one after another, in a continuous column, passing downwardly into the contained water of the tube. By application of sufficient pressure on each newly inserted bottle of a series the end-most bottle of the series passes outwardly of the delivery end 9, as long as bottles continue to be introduced.

In their passage downwardly through the tube and into the contained water, each bottle becomes filled, remaining full while submerged, and automatically draining as the bottles pass upwardly above the water line *a*, being delivered in practically dry condition. Dependent on the rate of travel, each bottle is thus exposed to the cleansing and sterilizing action of the heated liquid and is automatically subjected to the filling,

maintenance of the contents, and eventual emptying, requiring merely the introduction and removal of the bottles, one at a time, as the operation proceeds.

5 When desired the entire top or cover 5 with the connected tube or tubes may be bodily removed, leaving the interior of the tank open and unobstructed so that it may be used for washing or sterilizing larger 10 utensils, such as milk cans, or the like.

As will be understood, any desired number of tubes 7 may be utilized, such as two, so as to economize the time of operation with increased output.

15 The device is comparatively simple and cheap in construction, highly efficient in operation, strong and substantial, and not liable to get out of order. It is capable of use in the manner described and thoroughly 20 washes and subjects all interior and exterior portions of the bottles to the cleansing and sterilizing action of the liquid.

It may be made in various suitable sizes or may be changed in design or other detail 25 features of construction by the skilled mechanic, but all such changes are to be considered as within the scope of the following claims.

What I claim is:

30 1. In a sterilizing tank for bottles, the combination of a main vessel adapted to contain water and having a supporting bottom, outwardly and upwardly extending end walls having vertically extending upper 35 edges, parallel sides connecting the bottom and end walls and terminating on the horizontal plane of the end wall edges, a flat removable cover having interfitting flange connection with the side and end wall edges, 40 a tubular bottle containing and guiding conduit fixedly connected with and extending inwardly and downwardly from opposite end portions of the cover and rounded in the form of a depending arc with its middle 45 adjacent the vessel bottom, the lower portion of said conduit having a plurality of transverse openings.

2. In a sterilizing tank for bottles, the combination of a main vessel adapted 50 to contain water and having a supporting bottom, outwardly and upwardly extending end walls having vertically extending upper edges, parallel sides connecting the bottom and end 55 walls and terminating on the horizontal plane of the end wall edges, a flat removable cover having interfitting flange connection with the side and end wall edges, a tubular bottle containing and guiding 60 conduit fixedly connected with and extending inwardly and downwardly from opposite end portions of the cover and rounded in the form of a depending arc with its middle adjacent the vessel bottom the lower 65 portion of said conduit having a plurality

of transverse openings, the receiving end of the conduit being flush with the cover and the opposite delivery end projecting above the cover for delivery to a conveyor or the like.

In testimony whereof I affix my signature.

JAMES B. BAKER.
